BOBBIN HOLDER

Robert Rulon-Miller and Warner H. Tabor, Bristol, R. I., assignors to Dixon Corporation, a corporation of Rhode Island

Application June 3, 1954, Serial No. 434,142

8 Claims. (Cl. 242—130)

This invention relates to a bobbin holder of the type used for supporting a bobbin from the under side of the top board of the creel of a spinning frame or a roving frame.

Pendant type bobbin holders usually have been supported rotatably by means of ball bearings located outside of the bobbin and directly beneath the top board of the creel with a part which extends into the open center of the bobbin depending from this ball bearing for frictionally engaging the inner walls of the bobbin. There is considerable lint present around the creel of a spinning frame, and this lint settles on the ball bearings and their supports, thus increasing friction of the bearing, and is difficult to clean. Further, the use of a ball bearing requires that a brake be used to retard turning.

One of the objects of this invention is to completely house the bearing for the bobbin holder within the bobbin so that it will be protected from lint and thus will not be hampered by friction which results therefrom.

Another object of the invention is to provide a device which will turn easily without the necessity of providing ball bearings, which are expensive.

Another object of the invention is to provide an arrangement which will need no brake to control the rotation of the package.

Another object of the invention is to provide an arrangement so that the bobbin holder may be adapted for use with many different diameter bobbins.

Another object of the invention is to provide an arrangement so that the bobbin holder may be shifted for use with one size bobbin or for use with another size bobbin by a simple manual operation.

With these and other objects in view, the invention consists of certain novel features of construction as will be more fully described and particularly pointed out in the appended claims.

In the accompanying drawings:

Figure 1 is a sectional view of an enlarged scale showing a portion of the bobbin as secured in position by a holder employing this invention and illustrating the parts in position for receiving a smaller size bobbin;

Figure 2 is an elevation of the bobbin holder alone looking at right angles to the view of Figure 1;

Figure 3 is a section of the bobbin holder alone with the parts in position for taking a large size bobbin;

Figure 4 is a section on line 4—4 of Figure 2;

Figure 5 is a section on line 5—5 of Figure 3;

Figure 6 is a section on line 6—6 of Figure 1;

Figure 7 is a perspective view of the control member for changing the bobbin holder from one to receive a large bobbin to one to receive a small bobbin.

With reference to the drawings, 10 designates the top board of a creel of a spinning frame or the like from which my bobbin holder is suspended in pendant relation.

The bobbin holder comprises a head 11 having a threaded bore 12 into which screw 13 extends through opening 14 in the top board 10 of the creel of a spinning frame. The head 15 of the screw engages the margin

2

about the hole 14 and serves to draw the head 11 up against the under side of the top board so as to be substantially rigid therewith. The bore extends completely through the head 11 and is reduced as at 16 and again reduced at its lower end as at 17. The surface 18 between the bores 16 and 17 is formed on the arc of a sphere and a ball 19 is located in the bore 16, which ball is substantially the same size as the bore 16 having its bearing on the shoulder 18. Pin 20 extends through the opening 17 and is much smaller than this opening and has a forced fit with the ball 19 allowing rocking motion laterally of the axis of the head and bore in a swivel-like fashion.

The bobbin holding member designated generally 21 is formed of a single piece of sheet stock bent into a tubular form and comprising a body 22 having a hollow center 23. At diametrically opposite points slots 24 are provided, with which slots arms 25 register. These arms 25 extend generally downwardly from the upper portion of the body 22 extending from the end edge of the slot 24 and are formed of the same stock as this tubular body, the stock being in continuation from the upper end of the slot and being bent outwardly as at 26 and then downwardly as at 27 with the ends curving outwardly as at 28. These arms are arcuate in cross section to stiffen them and of a size smaller than the width of the slot 24 and may be freely flexed into the slot to the dotted line position shown in Figure 1.

At the lower end of the cylindrical tube 22 there is positioned the control member 30 which is shown in perspective in Figure 7. This control member has a cylindrical body portion 31 which has an annular recess 32 in its surface. This cylindrical portion 31 is of a size substantially the size of the interior surface of the cylindrical tubular body 22 and is rotatably mounted therein. It is prevented from being withdrawn from the end of the body by fingers 33 located at diametrically opposite points of the tubular member being turned into the slot 32 so as to retain this control member in place yet permit it to rotate. This control member is provided with two upstanding projections 34 located at diametrically opposite portions of the member and providing a slot 35 between them. These projections are of a height so that when the projections 34 are turned into registration with the slot 24, the arms 25 will engage these projections 34 and block the entry of the arms 25 into the slot as shown in the position illustrated in Figures 3 and 5. However, when the control member 30 is turned at right angles to this position, as shown in Figures 2 and 6, then arms 25 are free to move through the slots 24 into the space 35 between the projections, as shown in the dotted line position of Figure 1, and when in this position, the arms may take a smaller bobbin or one having a smaller central bore. When the arms are in engagement with the projections 34 so as to hold them outwardly, a larger bobbin will be accommodated and still the arms may flex by sliding along the projections 34.

An abutment 41 is provided on the pin 20 which engages the anti-friction washer 42 formed of any suitable anti-friction material. This washer in turn engages web 37 extending across the tube 22 with projections 38 entering slots 39 in the walls of the tube. This abutment 41 is made small so as to reduce resistance of the bobbin holding member 21 to turning with the bobbin. Relative rotation is between washer 42 carried by member 21 and the abutment 41. The ball 19 does not rotate with the bobbin. The lower end of the head is rounded or cut away as at 51 so as to allow full rocking movement of the pin 20 by reason of its ball mounting 19. Thus, in forcing the bobbin on to the holder 21, should there be a force out of line with the axial center of the bobbin, the contact of the face 22 of the holder with the rounded

end 51 of the head will be at a location to better support a thrust of this character.

The bobbin will have wound on it a package 45 and as the yarn is drawn from the outer surface of the package 46, the turning force will be a multiple of the pulling force times the distance 47 that the yarn is located from the turning axis of the bobbin. The resistance to this force which tends to turn the package will be the weight of the package multiplied by the co-efficient of friction between the abutment 41 and the washer 42 multiplied by the radius of the abutment 41, which radius we have designated by the arrow 48. Thus, it will be apparent that in order to have a low resistance to turning, we will maintain the radius 48 as small as possible consistent with the necessary strength to support the parts, and to do this the pin 20 will also be made small.

It will also be noted that when the bobbin is full and weighs the most, the radius 47 is the greatest, affording the greatest turning moment, whereas when there is less yarn on the bobbin, the radius 47 is the smallest. Thus, there is a tendency to equalize the force required throughout the use of the package. As the resistance to turning and the weight of the package always have an opposite relationship as to sizes, the resultant turning force required is always the same.

In order to assist in the provision of a lint free bearing, we provide a cover 49 having a flange 50 which is slideable on the head 11 and closes the bore of the bobbin at the top, thus resting on the bobbin and turning with it. Further, we provide a flange 53 on the head, which will catch lint should it enter the bobbin opening and arrange that the upper edge 52 of the bobbin holder come close to this flange to avoid lint entering the bobbin holder.

By this arrangement we find that the resistance to turning is small, making the ball bearing unnecessary and yet sufficient so that a brake is unnecessary.

We claim:

1. A bobbin holder comprising a tubular body having slots therethrough, resilient arms outwardly of the body connected to said body and located in registry with said slots and movable therethrough upon flexing, and abutments carried by said body and rotatable relative thereto into and out of registry with said slots to selectively block or permit the moving of said arms through said slots.
2. A bobbin holder as in claim 1 wherein said slots and said arms extend lengthwise of said body.
3. A bobbin holder as in claim 1 wherein said body is cylindrical and said abutments are rotatably mounted on said body at a fixed position thereon.

4. A bobbin holder as in claim 1 wherein said body is cylindrical and said abutments are rotatably mounted on said body at the lower portion thereof to be engaged by the free end portions of said arms.

5. A bobbin holder as in claim 1 wherein said arms are attached to the upper portion of the body and the abutments are rotatably mounted on the body at a fixed position at the lower portion thereof to be engaged by the free end portions of said arms.

10 6. A bobbin holder comprising a tubular body, said body having slots therethrough and resilient arms extending from the upper end of said slots in registry therewith, said arms being movable through said slots, a disk rotatably mounted on said body at the lower inner side portion thereof, said disk having spaced abutments thereon rotatable with said disk to a position in registry with said slots to block the free end of said arms from passing inwardly through said slots, said disk being rotatable to move said abutments out of registry with said slots to permit said arms to extend through said slots.

20 7. A bobbin holder comprising a member having a tubular body, resilient arms outwardly of the body movably mounted on said body, and means to selectively adjust said arms to each of a plurality of effective diameters for engaging a bobbin, said means comprising abutments engageable by said arms and rotatably mounted on said body at a fixed position thereon, said abutments being rotatable to a position to be in registry with said arms to be engaged thereby and rotatable to a position out of registry with said arms to be free the arms therefrom.

25 8. A bobbin holder comprising a member having a tubular body, resilient arms outwardly of the body movably mounted on said body and means to selectively tension the resiliency of said arms different amounts, said means comprising abutments engageable by said arms and rotatably mounted on said body at a fixed position thereon, said abutments being rotatable to a position to be in registry with said arms to be engaged thereby and rotatable to a position out of registry with said arms to free the arms therefrom.
